UNITED STATES PATENT OFFICE.

EMIL TYDEN, OF EVANSTON, ILLINOIS.

DRY-PIPE-VALVE-ACCELERATING DEVICE.

Application filed August 25, 1923. Serial No. 659,333.

To all whom it may concern:

Be it known that I, EMIL TYDEN, a citizen of the United States, and resident of Evanston, in the county of Cook and State 5 of Illinois, have invented certain new and useful Improvements in Dry-Pipe-Valve-Accelerating Devices, of which the following is a specification, reference being had to the accompanying drawings, forming a 10 part thereof.

The purpose of this invention is to provide for an improved construction in a dry pipe sprinkler system for accelerating the opening of the dry pipe main valve upon the 15 opening of a sprinkler head, with a specific purpose of preventing the opening of the main valve upon the occurrence of a negligible leakage in the air system amounting to less than would occur through a sprinkler 20 head opening. It consists in the elements and features of construction shown and described as indicated in the claims.

In the drawings:

Figure 1 is a front elevation of the dry 25 pipe main valve casing and connected water 001 and air pipes, equipped with devices embodying this invention, the casing being partly broken away at the side at which the hand hole is located, and shown in section radial with respect to the main valve 30 for disclosing the interseat chamber, hereinafter referred to as the atmospheric pressure chamber.

Figure 2 is an enlarged sectional view of 35 the interseat chamber as shown in Figure 1.

Figure 3 is a vertical section taken as indicated at line 3—3 on Figure 2.

Figure 4 is an enlarged vertical section 40 of the sylphons and their connections, viewed from the same direction as in Figure 1.

In the structure shown in the drawing, A is the dry pipe valve casing, B the water inlead pipe, C the pipe leading to the 45 sprinkler system which, in the normal condition of the apparatus, when set for its purpose, is occupied by air under compression. D is the dry pipe main valve having the usual construction for seating at two 50 concentric seats, A¹⁰ and A¹¹, between which there is the usual interseat chamber, a, in which the pressure is normally atmospheric, so that the super-atmospheric air pressure, 55 operating above the valve D, over the larger area defined by the outer seat A¹¹, as compared with the area defined by the inner seat

A¹⁰, over which the water pressure is operative, insures the valve D being held seated by a super-atmospheric pressure in the system of about 30 lbs., against water pressure 60 in the main which may reach 100 lbs. When a sprinkler head is opened, causing reduction of the super-atmospheric pressure in the system, which eventually results in the dry pipe main valve D being opened by the 65 water pressure and the water thereby being sent to the open sprinkler head, it is desirable that the opening of the valve should be delayed as little as possible after the sprinkler head is opened and the reduction 70 of air pressure in the system begins; but when only a single sprinkler head is opened by the fire, it may require a very appreciable length of time for the air pressure to be reduced so as to permit the dry pipe main 75 valve to open. The purpose of the present invention is to cause the amount of reduction of air pressure in the system which will be experienced almost instantly upon the opening of a single sprinkler head, to 80 result in overcoming the differential pressure upon the upper side of the valve which holds it seated, so that the valve will open almost instantly upon the opening of the 85 sprinkler head. This is effected by means of devices which are sensitive to the slight reduction of pressure which occurs almost instantly upon the opening of the sprinkler head, and which, responding to that slight reduction, operate to open communication 90 from the region of air pressure above the dry pipe main valve, to the interseat or atmospheric pressure chamber below that valve.

Figure 4 is an enlarged vertical section of the sylphons and their connections, viewed from the same direction as in Figure 1. In the structure shown in the drawing, A is the dry pipe valve casing, B the water inlead pipe, C the pipe leading to the 95 sprinkler system which, in the normal condition of the apparatus, when set for its purpose, is occupied by air under compression. D is the dry pipe main valve having the usual construction for seating at two 100 concentric seats, A¹⁰ and A¹¹, between which there is the usual interseat chamber, a, in which the pressure is normally atmospheric, so that the super-atmospheric air pressure, 105 operating above the valve D, over the larger area defined by the outer seat A¹¹, as compared with the area defined by the inner seat

The dry pipe main valve, D, has a port, a⁵, which is closed by a downwardly seating valve, a⁶, said port leading from the region of air pressure above the dry pipe main valve to the interseat or atmospheric pressure 110 chamber, a, below that valve. The interseat chamber, a, has a drainage port, a⁷, at the bottom in vertical alignment with the port, a⁵, and valve, a⁶. The valve, B', which controls its drainage port seats at the lower 115 end of said port, being carried on a stem actuated, as hereinafter described, and hav-

ing that stem extending up through the drainage port and long enough to encounter and thrust upwardly from its seat the valve, a^6 , by the time the drainage valve, B^7 , reaches its seat.

A branched pipe fitting, G, connected at any convenient point into pipe, C, carries at its two branch extremities respectively, similar bellows-like elastically expansible 10 and contractible devices of the character commonly known as "sylphons", hereinafter so referred to as sylphons, H and J, which are ultimately equally expanded by the air pressure admitted to them through unequal 15 restricted ports, h and j , formed in the disks, h^1 and j^1 , interposed at their respective connections with the fitting, G. Upon reduction of the pressure in the pipe, C, to the amount which will result from opening 20 of a single sprinkler, the sylphon, H, having the larger port of communication with the air pressure, will experience the reduction instantly while the sylphon, J, having a much more restricted port of communication, 25 will be relieved very slowly and not appreciably before the sylphon, H, has collapsed enough for operating the connected devices about to be described.

Upon the upwardly projecting stems, H^2 and J^2 , of the sylphons, J and H, there is mounted pivotally with respect to both sylphons, a lever K, the pivotal connection with the sylphon, H, being slotted for accommodating the movement of the lever, K, 35 rocking about its pivot to the stem of the other sylphon, J.

On a stud, A^9 , jutting horizontally from the dry pipe valve casing, A, there is mounted an eccentric cam, E, provided with a 40 spring, F, connected at one end with the cam and at the other end with the support of the latter. Pivoted on the valve casing, A, by means of a rock-shaft, L^1 , is a latch, L, which engages a notch, e, in the hub of the cam, E, for locking the cam at a position 45 at which the spring, F, is tensioned to a desired degree and at which one end of a lever, T, which is fulcrumed on the valve casing, A, and at the other end connected with the stem, b^7 , of the drainage valve, B^7 , is in contact with the periphery of the cam at the point of least radius of the latter. An arm, K^1 , of the lever, K, depends alongside the latch, L, and has an abutment, k^1 , 55 which is in touch laterally with the latch at the normal position of said lever, K,—i. e., when the sylphon, H, is collapsed before the collapse of the sylphon, J, occurs. The rocking of the lever, K, causes it to swing its arm, K^1 , sidewise, and causes the abutment, k^1 , 60 acting against the up-standing arm, L^2 , of the rock shaft, L^1 , to actuate the latch in the direction for disengaging it from the cam, E, and the cam being thereupon actuated by its spring for rocking it over its

fulcrum, actuates the lever, T, in the direction for thrusting up the drainage valve, B^7 , to its seat, and in that movement by means of the interiorly extending stem of the drainage valve, thrusting the valve, a^6 , 70 open and admitting the pressure from above the dry pipe main valve into the atmospheric pressure or interseat chamber, a , whose atmospheric communications through the drainage port is closed by the same 75 movement.

It will be understood in the foregoing description that the operation of the structure described is designed to be that upon reduction of the pressure in the air pressure region which results from opening of a single sprinkler head, the unequal collapse of the sylphons which occurs instantly, causes the opening of the valve, a^6 , and admission of the air pressure from above the valve to 80 the chamber below the valve, overcoming the differential by which the valve has been held seated, causing it to be opened by the water pressure, which is the result desired.

In resetting the entire structure, the operator can hold the drainage valve, B^7 , seated for any purpose for which it may be desirable in the set-up to have the chamber, a , closed and filled with water up to the instant of initially seating the dry pipe main valve, 90 simultaneously with which the operator will release the drainage valve, B^7 , permitting the interseat chamber to drain; and the operator will then manually rock the cam, E, over to position for engagement by its latch, 95 L. Both sylphons, in the meantime, within a few seconds after having operated as above described, for releasing the cam latch, will have become equally inflated, and in the introduction of air pressure to the system in the set-up, they will expand equally and thereby cause the abutment, k^1 , on the lever arm, K^1 , to move up alongside the latch without operating it for disengaging it from the cam. 100

A drainage spout, P, is desirably applied around the drainage port, a^7 , connected with a drain pipe, P^1 . The downwardly extending stem of the drainage valve, B^7 , extends through an aperture in the lower side of this spout without causing any unobjectionable leakage during the drainage.

I claim:—

1. In a dry pipe sprinkler system, in combination with a dry pipe main valve, constructed for exposing different areas to the water and air pressures respectively, at its opposite sides, and having for that purpose, at the water inlet side, a chamber in which the pressure is normally substantially atmospheric; a port through the dry pipe main valve for communicating from the air pressure region beyond said valve to said atmospheric pressure chamber; a valve controlling said port; means in the atmospheric 120

125

130

pressure chamber for opening said valve; an
expansible and reducible chamber device ex-
posed to the air pressure from the system
reaching different areas of the moving wall
5 of said device through two unequal ports,
whereby change of air pressure in the sys-
tem causes temporarily unequal pressures at
said different areas, and connections from
said device for actuating said valve open-
10 ing means.

2. In the construction defined in claim 1,
foregoing, the atmospheric pressure cham-
ber having a drainage port, the valve open-
15 ing means comprising a thrust member
which extends in through said drainage
port, and which is exposed outside said
chamber for actuation in its valve opening
movement.

3. In the construction defined in claim 1,
20 foregoing, the atmospheric pressure chamber
having an aperture opposite the port
through the main valve, the valve opening
means comprising a thrust member which
extends from outside the dry pipe valve cas-
25 ing in through said aperture, said thrust
member being exteriorly exposed for actua-
tion in its valve opening movement, and

carrying a valve element, which, at the limit
of its valve opening thrust, seats at the outer
30 side of the aperture through which the thrust
member extends.

4. In the construction defined in claim 1,
foregoing, the connections from the expan-
sible and reducible chamber device for actu-
ating valve opening means, comprising a 35
cam which is rotated by the movement of
a moving wall of said chamber; a lever ful-
crumed outside the dry pipe valve casing,
having one end positioned for actuation by
the rotation of the cam, a thrust member ex-
tending through the wall of the atmospheric
40 pressure chamber for encounter within said
chamber for opening the valve at the port
through the dry pipe main valve and at its
outer end, exposed for actuation by the other
45 end of the lever, said thrust member carry-
ing a valve element which seats at the outer
side of the aperture through which said
thrust member extends in the atmospheric
50 pressure chamber.

In testimony whereof, I have hereunto set
my hand at Chicago, Illinois, this 16th day
of August, 1923.

EMIL TYDEN.
